(57) **CLAIM**

The ornamental design for an air conditioner controller, as shown and described.

DESCRIPTION

FIG. 1 is a front perspective view of an air conditioner controller showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the indicia on the upper surface and a central rectangular region on the lower surface of the air conditioner controller represents unclaimed subject matter and forms no part of the claimed design.
